John J. Armstrong of Prairie du Chien

Letter Patent No. 2497 Dated Oct. 30th 1866

Design for a Military Monument.

The Schedule referred to in this Letter Patent and making part of the same.

To all whom it may concern.

Be it known that I, John J. Armstrong of Prairie du Chien in the County of Crawford and State of Wisconsin have invented a new and improved mode of building, designing and erecting soldier's monuments, Military, County and State Monuments, and I do hereby declare that the following is a full, and exact description thereof reference being had to the accompanying drawings, and to the letters of reference, marked theron:

The nature of my invention consists in erecting, or placing, dry, small pedestals or ornaments around the main monument, these small pedestals to be made of marble, surrounded with a base made of marble, bronze or other suitable materials. The pedestals are shown as lettered C, in the accompanying drawings.

What I claim as my invention and desire to secure by Letter Patent is:

a. Design for a monument, as shown and described.

Witness,

O. B. Thomas.

A. McCarty.
